UNITED STATES PATENT OFFICE.

JIMMIE SLEDGE, OF SMITHVILLE, TEXAS.

DESIGN FOR A COMBINATION OUTERGARMENT.

Application filed February 28, 1923. Serial No. 5,306. Term of patent 14 years.

To all whom it may concern:

Be it known that I, JIMMIE SLEDGE, a citizen of the United States, residing at Smithville, in the county of Bastrop and State of Texas, have invented a new, original, and ornamental Design for a Combination Outergarment, of which the following is a specification, reference being had to the accompanying drawing, forming part thereof.

I claim:

The ornamental design for a combination outer garment, as shown.

JIMMIE SLEDGE.
